CONDUIT UNION SEAL-OFF FITTING

Merle A. Plummer, North Hollywood, Calif., assignor to
Myers Electric Products, Inc., Los Angeles, Calif.

Filed May 21, 1970, Ser. No. 23,074

Term of patent 14 years

Int. Cl. D13—03

U.S. Cl. D26—1

FIG. 1 is an elevational view of a conduit union seal-off fitting showing my new design.

FIG. 2 is a top plan view thereof.

FIG. 3 is a bottom plan view of the same.

FIG. 4 is an exploded elevational view thereof.

I claim:

The ornamental design for a conduit union seal-off fitting, substantially as shown.
